WATER TREATMENT PLANT OR THE LIKE

James A. Mixon, Jacksonville, Fla., assignor to General Utility Equipment, Inc., Jacksonville, Fla.

Filed Nov. 26, 1971, Ser. No. 202,735

Term of patent 14 years

Int. Cl. D23—01

U.S. Cl. D23—3

FIG. 1

FIG. 2

FIG. 3

FIG. 4

FIG. 5

FIG. 1 is a top plan view of a water treatment plant or the like showing my new design;

FIG. 2 is a front elevational view thereof;

FIG. 3 is a rear elevational view thereof;

FIG. 4 is a right end elevational view thereof; and

FIG. 5 is a left end elevational view thereof.

I claim:

The ornamental design for a water treatment plant or the like, substantially as shown.
